DESIGN FOR A GAME DEVICE

Burton Daniels, New York, N. Y.

Application October 9, 1942, Serial No. 103,478

Term of patent 3½ years

To all whom it may concern:

Be it known that I, Burton Daniels, a citizen of the United States, residing at New York, in the county of New York and State of New York, have invented a new, original, and ornamental Design for a Game Device, of which the following is a specification, reference being had to the accompanying drawing, forming a part thereof.

Fig. 1 is a perspective view of a game device, showing my new design.

Fig. 2 is a side elevational view of the same.

Fig. 3 is a plan view of the device with the horizontal board shown in Fig. 1 removed and the central outside feature in upright or normal position.

Fig. 4 is a rear elevational view of Fig. 1.

I claim:

The ornamental design for a game device, as shown.

BURTON DANIELS.
